REFRIGERATED CHEST OR SIMILAR ARTICLE

James Robert Reichow, Edina, Minn., assignor to The Cornelius Company, Anoka, Minn., a corporation of Minnesota

Filed Apr. 14, 1964, Ser. No. 79,498

Term of patent 14 years

(Cl. D67—3)

FIG. 1 is a front perspective view of a refrigerated chest showing my design.

FIG. 2 is a rear perspective view thereof.

The narrow slightly recessed stripe in the slightly domed cover extending from either side of the oval indicia-bearing means is of a contrasting color.

The dominant features of my design reside in the portions shown in full lines.

I claim:

The ornamental design for a refrigerated chest or similar article, substantially as shown and described.
